UNITED STATES PATENT OFFICE.

LESLIE C. MESKIMEN, OF WATERLOO, IOWA.

REVERSING-VALVE MECHANISM FOR INTERNAL-COMBUSTION ENGINES.

1,087,033.

Specification of Letters Patent. Patented Feb. 10, 1914.

Application filed January 29, 1913. Serial No. 744,939.

To all whom it may concern:

Be it known that I, LESLIE C. MESKIMEN, a citizen of the United States, residing at Waterloo, in the county of Blackhawk and State of Iowa, have invented new and useful Improvements in Reversing-Valve Mechanism for Internal-Combustion Engines, of which the following is a specification.

This invention relates to reversing valve mechanism for internal combustion engines, the object in view being to provide an extremely simple valve arrangement, especially adapted for use in connection with four-cycle internal combustion motors, the arrangement being such that the relative positions of the valve and valve gear may be quickly and easily changed, so as to adapt the engine to operate in either direction desired.

Another object of the invention is to provide, in connection with a valve gear wheel and a cam mounted thereon, locking means for holding the cam in either one of two positions, to which it is adapted to be adjusted.

With the above and other objects in view, the invention consists in the construction, combination and arrangement of parts, as will be hereinafter more fully described, illustrated in the accompanying drawings, and pointed out in the claims hereunto appended.

In the drawings: Figure 1 is a view in elevation, looking toward the outer face of the cam gear of an internal combustion engine, illustrating the two positions of the cam carried by said gear wheel. Fig. 2 is an inner face view of the same.

Referring to the drawings, 1 designates the usual cam gear wheel, or in other words, the gear wheel which is mounted on the cam shaft 2 of an internal combustion engine, said gear 1 being usually made twice the size of the gear wheel on the engine shaft, so that the cam shaft 2 will revolve at half the speed of the engine shaft.

In carrying out this invention, the cam 3 which operates the valve of the motor is provided with a hole, adapting it to be mounted on the shaft 2, said cam fitting loosely on the shaft, so that it may be turned to either one of two positions, as illustrated in Fig. 1, the cam, when occupying one position, being adapted to operate the valve, so as to cause the engine to turn in a corresponding direction, and when the

cam is reversed or turned to the other position indicated, it will cause the engine to operate in the opposite direction.

The means for shifting the cam will now be described.

The cam is provided at a suitable point with a pin 4 which is adapted to move lengthwise of an arcuate slot 5 formed in the body of the gear wheel 1, as shown in Fig. 1, said slot 5 being concentric with the shaft 2. The slot 5 is just of sufficient length to admit of the necessary movement of the pin 4 to hold the cam 3 at the extreme limit of its movement in opposite directions, and in order to lock the cam in its adjusted position on the gear 1, I provide a locking dog 6, having the end thereof concaved, as shown at 7, forming a shoulder which is adapted to bear against the pin 4 in the manner illustrated in Fig. 1.

The locking dog 6 is pivotally mounted, at 8, on the cam gear 1, and has connected thereto one end of a coiled spring 9, the tension of which is exerted on the dog 6 to hold the end thereof in engagement with the pin 4 of the cam 3. When it is desired to reverse the direction of rotation of the engine, the locking dog 6 is thrown out of engagement with the pin 4, and the cam is then turned, so as to move the pin 4 from one end of the slot 5 to the other. After this is done, the locking dog 6 is again thrown into engagement with the pin 4, thereby locking said pin at the opposite end of the slot 5. It will be observed that the spring 9 serves to maintain a positive engagement between the locking dog 6 and the pin 4 of the cam, thereby preventing any possible accidental inopportune shifting of the cam, during the operation of the engine.

What is claimed is:

1. The combination with the cam shaft of an internal combustion motor, of a gear wheel mounted thereon and driven from the engine shaft, said gear wheel being provided with an arcuate slot concentric to the cam shaft, a cam journaled on the cam shaft at one side of said gear wheel, a pin on said cam movable lengthwise of said slot, and a pivoted locking dog for engaging and holding said pin at either end of the slot.

2. The combination with the cam shaft of an internal combustion motor, of a gear wheel mounted thereon and driven from the engine shaft, said gear wheel being provided with an arcuate slot concentric to the cam

shaft, a cam journaled on the cam shaft at one side of said gear wheel, a pin on said cam movable lengthwise of said slot, a pivoted locking dog for engaging and holding 5 said pin at either end of the slot, and a spring for maintaining the engagement between said locking dog and pin.

In testimony whereof I affix my signature in presence of two witnesses.

LESLIE C. MESKIMEN.
